UNITED STATES PATENT OFFICE.

JOHN JOSEPH DEVINE, OF MIDDLETOWN, CONNECTICUT.

WRITING-LIGHTING DEVICE.

1,418,132.

Specification of Letters Patent. Patented May 30, 1922.

Application filed April 24, 1920, Serial No. 376,384. Renewed April 4, 1922. Serial No. 549,471.

To all whom it may concern:

Be it known that I, JOHN JOSEPH DEVINE, a citizen of the United States, residing at Middletown, in the county of Middlesex and State of Connecticut, have invented certain new and useful Improvements in Writing-Lighting Devices, of which the following is a specification.

My invention relates to improvements in writing-lighting devices, involving certain features shown and described in the patent granted to me May 2, 1916, No. 1,181,509, which had relation to a fountain pen that was provided with an electrical device which could be operated to illuminate the portion of the surface with which the pen point was engaged, and the object of my present improvement is to produce a device that is operative substantially in the same manner as the device mentioned so far as concerns the cooperation of the illuminating effect with the writing pen point, and which in addition is provided with a second writing device in the form of a pencil and which is also provided with illuminating means for illuminating the surface with which the writing pencil point is engaged, whereby alternatively either the pen or the pencil can be used for writing, as desired, and the end portion that is not in use for writing or is inactive is adapted to serve usefully as a lighting device for general illumination within a relatively limited range for lighting some other surface than the one with which the particular lighting device happens to be engaged.

In the accompanying drawing:

Figure 1 is a side elevation of my improved writing-lighting device.

Figure 2 is a plan view of the same.

Figure 3 is a similar view with the electric cell removed.

Figure 4 is a fragmentary plan view with the adapter for connecting with the electric cell removed.

Figure 5 is a side elevation of the body, in part broken away, to show the ink reservoir and connecting channel.

Figure 6 is a longitudinal sectional view on the line 6-6 of Fig. 2.

Figure 7 is a sectional view on the line 7-7 of Fig. 6.

Figure 8 is an enlarged sectional view showing the adapter and adjacent parts.

Figure 9 is a fragmentary end elevation of the removable cap that is used on the end of the device that is provided with the writing device in the form of key device, with a projection of square form, that is adapted for use in removing the plug cap for the ink reservoir.

Figure 10 is fragmentary side elevation of the key device shown in Fig. 9 in position for use, with the square end entered into the cooperating opening in the reservoir plug cap.

Figure 11 is a view part in side elevation and part in longitudinal section of the pen point end portion of a modified form of structure that is adapted to have the body structure made of metal.

Figure 12 is a similar view of the pencil point end portion of the modification referred to above.

Figure 13 is a fragmentary sectional view of the modification referred to, showing the details of the plug for closing the opening in the side wall of the body structure, comprising the means for receiving and supporting the lamp and also for receiving and supporting the adapter and the current supply device connected with the adapter.

My improved writing-lighting device comprises a body 10 that is generally of tubular form with open ends and which provides at the two ends housings for writing devices, that at one end shown at the left end in Fig. 5, being in the form of a fountain pen structure 11, and that at the other end, at the right, being in the form of a lead pencil 12, and which provides at the middle portion a housing for an electric lamp 13, which is positioned so as to provide an illuminating effect for a limited zone, as determined generally by the size of the tubular body 10 and the shape thereof, and in which zone is included the writing point 14 of the pen 11 on the one side and the pencil point 15 on the other side of the lamp. Provision is made for operatively supporting a current supply device 16 on the upper side of the body 10 of common form for flash-light use, in which is housed a suitable electric cell or battery and has a shut-off device or switch that is operated in a convenient way by means of a trip device or setting device 17 that is exposed and accessible for turning the light on and off.

100
105

The ends of the body 10 are provided with removable caps or covers comprising the cap 18 at the pencil end 12 and the cap 19 at the pen end 11. 5 The cap 18 at the pencil end has a simple rounded outer end 20. The end 21 of the cap 19 at the pen end is also rounded, but is provided at the tip end portion with a tip or projection 22 that, as shown, is of square formation so as to be adapted to serve as a key for tightening and for removing the screw plug cap 23 that is positioned in the top wall portion 24 of the body 10 and has a recess 25 of corresponding form, suitably 10 to cooperate therewith.

The cap plug 23 serves as a closure for the upper end of a trench or channel 65 that leads around the inside of the body 10 and terminates at the shallow reservoir 26 that 15 is provided on the under side of the body 10.

The reservoir 26 is substantially of the same form as that shown and described in the patent referred to above and connects in a similar manner by means of a radial duct 27 with an auxiliary reservoir 28 that is provided in the axially supported body structure 29 of the fountain pen structure 11, which is supported by a set of spider arms 30, also as in the patent mentioned. 25

The duct 27 and the arms 30 are substantially relatively thin, fin-like structures, such as to be adapted to serve their particular functions with a minimum obstruction of light from the lamp 13. 30

I find it advantageous in use to provide a relative concentration of light adjacent the under side of the writing point, both for the pen 14 and the pencil 15, and this effect I obtain by providing an extension 31 of the tubular body 10 on the corresponding side thereof that serves as a reflector for light from the lamp 13, which lamp is positioned approximately in the middle of the body 10. 35

The pencil 12 is supported by means of an axially positioned sleeve 32 so as to be longitudinally slideable therein, the said sleeve 32 being itself supported by means of a set of spider arms 33, and access to the pencil 12 by means of a sharp pointed instrument 45 or pin or the like for feeding the pencil along is provided by means of registering slots in the sleeve and body wall, comprising the slot 34 in the sleeve 32 and the slot 35 in the body 10. Frictional resistance for holding the pencil 12 in the position to which it may set is provided in the form of the three pointed dog plate 36 that is supported by means of screws 37 from one of the spider arms 33, as shown. The active 50 or engaging point 38 of the said dog plate 36 extends through a slit 39 in the sleeve 32 and penetrates slightly into the side wall of the pencil 12.

The lamp 13 is admitted to the interior of 65 the body 10 through an opening 40 in the

side wall thereof, the side wall of which opening 40 is provided with a screw thread for receiving a plug 41 that serves as the support for the entire lighting mechanism, consisting of the lamp 13, the current supply and control device 16, and the intermediate supporting and connecting devices. The said intermediate devices comprise the screw sleeve 42 and the adapter 43. 70

Considering the details of these parts, the supporting plug 41 has an axial opening that is composed of the lower end portion 44 that is screw threaded and the upper end portion 45 in the form of an enlargement. 75

The screw sleeve 42 extends substantially 80 entirely through the said opening, has a screw thread for the entire length of the exterior portion or outside wall that fits and extends through the threaded lower end portion 44, so that the upper end portion 46 of the screw sleeve 42 projects upwardly within 85 in the enlargement or recess 45.

The interior wall of the screw sleeve 42 is also screw threaded for the entire length and fits the screw threaded shell portion 47 of the lamp 13 and the said lamp 13 is 90 screwed therein from the under or inner side, so that the bulb portion 48 of the lamp 13 will be positioned approximately at the middle of the body 10 and the connecting tip 49 of the lamp 13 will project upwardly above 95 the top face or end face of the said screw sleeve 42.

The current supply device 16 is provided with a socket opening 50 that is substantially 100 the counterpart of the structure of the connecting end of the lamp 13, comprising the screw sleeve portion or shell 47 and the tip 49, which serves as the means for mechanical and also electrical connection of the 105 lamp with the said supply device 16. In the present structure the shell 47 is supported by the screw sleeve 42 which latter provides the electrical connection with this particular part. The screw sleeve 42 is made 110 of metal and the supporting plug is made of hard rubber.

The screw sleeve 42 and the lamp tip 49 are connected with the receiving socket 50 through the medium of the adapter 43 as 115 follows:—The lower portion 51 of the adapter 43 is in the form of a bell structure that has an interior screw thread for being entered upon the upwardly projecting upper end portion 46 of the screw sleeve 42 and the upper end portion is in the form of a threaded sleeve 52 that is adapted to screw into the threaded portion 53 of the receiving socket 50, and which has fixedly supported in the bore a rod 54 for connecting the tip 49 125 of the lamp with the tip 55 in the socket 50. The said rod 54 is insulated from the threaded sleeve 52 by suitable insulation 56 and has a head 57 at each end that serves for 130 effecting the contact.

As described, the entire lighting mechanism is removable from the body 10 with the supporting plug or cap 41.

The screw sleeve 42 and the adapter 43 5 combine to form an adapting device whereby a current supply device of standard form is adapted for use with a lamp of standard form.

In the structure described, the body 10 10 may be made of hard rubber.

In Figs. 11, 12, and 13 are shown details of a modified form of structure in which the body 10^a may be made of metal.

Considering the structure of the pen point 15 end portion shown in Fig. 11, the fountain pen device 11^a is provided with a sleeve 60 of hard rubber that is interposed between the exterior supporting sleeve 61 of metal, and the interior parts, comprising the body 20 portion 62 of the pen, and the channeled plug 63, that are fitted together and combine to fill the bore of the said sleeve 60.

Considering the pencil end portion shown 25 in Fig. 12, the pencil 12^a is housed in a sleeve 32^a of metal, and the friction point device 38^a that serves to hold the pencil in the adjusted position is in the form of an inward indentation of the material of the said tube or sleeve 32^a.

30 Considering the structure for supporting the lamp and adjacent parts shown in Fig. 13, the lamp receiving opening 40^a is closed by a screw plug 64 that is made of metal and combines generally the functions of the plug 35 41 and the screw sleeve 42 for receiving the lamp 13 and the adapter 43, having on the upper end portion an annular slot 45^a for admitting the bell structure 51 of the adapted 43.

40 I claim as my invention:—

1. A writing-lighting device having a tubular body that is open at the ends, a writing device projecting from one of the said ends, and a lighting device located within 45 the said body and positioned therein so as to permit the light therefrom to be projected laterally through both of the said open ends.

2. A writing device as described in claim

1, and having a second writing device projecting from the other of the said ends of the tubular body.

3. A writing-lighting device in the form of tubular structure having a generally open interior, a writing device positioned at one end of the said structure, a lighting device positioned in the said interior, a reservoir connected by a delivery channel with the said writing device, a filling opening for the said reservoir being provided in the wall 60 of the said structure and connected to the said reservoir by a connecting channel, and the said reservoir and filling opening being disposed on opposite sides of the said structure. 65

4. In a writing-lighting device, a body of tubular form, a writing device projected from one end of the said body, and a lighting device housed within the interior of the said body, and the said body having on one 70 side of the said writing device an extension for reflecting light from the said lighting device to the writing point of the said writing device.

5. A writing-lighting device comprising 75 a body of tubular form with open ends, a lamp housed in the interior of the said body and adjacent the middle thereof, and a writing device located at each of the end portions of the said body, one being in the form 80 of a fountain pen structure and the other in the form of a lead pencil, the means for supporting the said writing devices being of skeleton form so as to reduce to a minimum the obstruction of light from the said lamp 85 outwardly towards the said open ends.

6. In a writing-lighting device, a tubular casing having a writing device at one end, a lighting device projected from the side wall 90 into the interior of the casing for providing illumination for the writing device, a battery structure for providing current for the lighting device, and an adapter structure positioned intermediate the said battery structure and lighting device serving as the 95 mechanical support for the said battery device and as the electrical connecting means.

JOHN JOSEPH DEVINE.
